US00D888236S

(12) **United States Design Patent** (10) **Patent No.:** **US D888,236 S**
(45) **Date of Patent:** **** Jun. 23, 2020**

(54) **CATHETER ADAPTER GRIP**

(71) Applicant: **Becton, Dickinson and Company**,
Franklin Lakes, NJ (US)

(72) Inventors: **Jonathan Karl Burkholz**, Salt Lake
City, UT (US); **Ralph L. Sonderegger**,
Farmington, UT (US); **Bart D. Peterson**, Farmington, UT (US); **Bin Wang**, Sandy, UT (US); **Nathan Mitchell**, Murray, UT (US)

(73) Assignee: **Becton, Dickinson and Company**,
Franklin Lakes, NJ (US)

(**) Term: **15 Years**

(21) Appl. No.: **29/670,731**

(22) Filed: **Nov. 19, 2018**

Related U.S. Application Data

(62) Division of application No. 29/580,131, filed on Oct. 5, 2016, now Pat. No. Des. 837,368.

(57) **CLAIM**

The ornamental design for a catheter adapter grip, as shown and described.

DESCRIPTION

FIG. 1 is a perspective front, top and side view of a catheter adapter grip having a single stabilization platform.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines represent portions of the catheter adapter grip that form no part of the claimed design.

1 Claim, 6 Drawing Sheets
